(57) **CLAIM**

I claim the ornamental design for make-up decals, as shown and described.

DESCRIPTION

FIG. 1 is a front view of the make-up decals.

FIG. 2 is a rear view of the claimed design.

FIG. 3 is a right side view of the claimed design.

FIG. 4 is a left side view of the claimed design.

FIG. 5 is a top view of the claimed design.

FIG. 6 is a bottom view of the claimed design.

FIG. 7 is a perspective view of the claimed design.

FIG. 8 is a perspective view of the claimed design showing the decals exploded from the backing strip. The broken lines appearing on FIG. 8 are for alignment purposes and form no part of the claimed design; and,

FIG. 9 is a perspective view of the claimed design showing the end user removing the decal from the backing strip of the claimed design. The broken lines appearing on FIG. 9 of a hand are environmental matter forming no part of the claimed design.
